UNITED STATES PATENT OFFICE

WALTER EVERETT MOLINS, OF DEPTFORD, LONDON, ENGLAND

CIGARETTE-MAKING MACHINERY

Application filed August 19, 1927, Serial No. 214,203, and in Great Britain August 27, 1926.

This invention is for improvements in or relating to cigarette making machinery and more particularly to a cigarette making machine of the continuous rod type wherein tobacco located within a hopper is automatically fed to the rod forming mechanism.

The consistency of the cigarettes manufactured by a machine of the above character depends largely upon the quality of the tobacco employed and the manner in which the same is fed to the machine. Thus if the tobacco employed comprises a heterogeneous mass of long and short shreds of tobacco, the weights of the cigarettes produced are liable to vary within wide limits due to the consistency of the tobacco varying at different parts, with the result that the cigarettes produced vary considerably and the variations depend to a considerable extent upon the ratio in which the long and short shreds are present in the tobacco.

Further, it is found that if the tobacco in the hopper is not maintained at a constant level, the weights of the cigarettes produced by the machine are liable to vary, as also is the case when the tobacco is allowed to accumulate in dense masses without being opened out before being fed to the carding mechanism which feeds the tobacco to the rod forming mechanism.

The accumulated errors produced by the above defects produce cigarettes of varying consistency, and it is an object of the present invention to provide means whereby the defects may be corrected before the tobacco is fed to the rod forming mechanism.

The present invention consists of a tobacco feeding apparatus for a cigarette making machine of the continuous rod type, wherein the tobacco is automatically fed to the tobacco hopper by means operable to separate automatically the long and short shreds of tobacco from one another.

The invention is more particularly described with reference to the accompanying drawings, in which:—

Fig. 1 illustrates in sectional side elevation a cigarette making machine of the continuous rod type to which the present invention is applied.

Fig. 2 is a detailed sectional side elevation of the tobacco elevating and shifting mechanism.

Fig. 3 is a plan view of Fig. 1 in direction of arrow "A".

Fig. 4 is an enlarged side elevation of the tobacco elevating elements of the mechanism which comprises the subject matter of the present application.

Fig. 5 is a part plan view of Fig. 4.

Fig. 6 is a cross section of the worm conveyor on the line C—C of Fig. 1, and

Fig. 7 is a section on the line D—D of the auxiliary hopper illustrated in Fig. 3.

Referring to the drawings, the tobacco elevator and sifter which constitutes the subject matter of the present application are shown applied to a tobacco feeding apparatus of the type set forth in British Patent No. 249,575.

The tobacco elevating and sifting mechanism comprises a receptacle 1 which is adapted to extend upwardly towards the feeding roller 2 of the tobacco hopper.

Mounted in the receptacle 1 are a series of elevating elements 3 which are provided with teeth 4 arranged to incline upwardly. The elevating elements 3 are adapted to reciprocate in an upward direction in such a manner that each alternate element is adapted to reciprocate out of phase relatively to its neighbour.

One set of elevating elements 3 are carried upon spindles 5 and 6, the remaining set of elements being carried upon spindles 7 and 8. The spindles 5 and 6 are connected through cranks 9 and 10 to sprocket wheels 11 and 12 and the spindles 7 and 8 are connected through cranks 13 and 14 to sprocket wheels 15 and 16. Sprocket wheel 15 is driven from the main drive of the machine through pinions 17 and 18, and the sprocket 15 is arranged to drive the sprockets 11, 12 and 16 through chains 19 arranged to pass over the said sprockets and held in contact therewith by yieldingly controlled idlers 20.

The ends of the elevating elements 3 which are located adjacent to the feeding roller 2 are curved inwardly so as to form to-

gether with the upper surface of the roller 2 the base of the main hopper to which the long shreds of tobacco are fed.

The elevating elements 3 are separated from one another by spaces (Figs. 3 and 5) which are arranged to permit the short shreds of tobacco separated from the long shreds to fall between the elevating elements on to the back wall 21 of the receptacle 1 from which they fall into a trough 22 in which is arranged a worm 23 which is operable to move the short shreds of tobacco to one end of the trough 22 and deposit the same in an upwardly directed channel 24 in which is arranged to rotate an upwardly directed worm 25 which feeds the short shreds of tobacco upwardly to an auxiliary hopper 26 in which is arranged a worm 27 which feeds the short shreds of tobacco along the auxiliary hopper and allows the same to fall through a slot 28 (Fig. 6) formed in the base of the hopper 27 on to the mass of long shreds of tobacco which is located in the space above the feed roller 2 and the combing roller 29. The feed roller 2 is preferably carded and the short shreds of tobacco which fall between the roller 2 and the combing roller 29 are carried around the scoop 30 and allowed to fall upon the back wall 21 of the receptacle 1 into the trough 22 from which they are removed to the auxiliary hopper hereinbefore referred to.

Thus it will be seen that if a mass of tobacco is placed in the receptacle 1, the reciprocating elevating elements 3 feed the same upwardly in steps and at the same time vigorously vibrate the tobacco, allowing the short shreds of tobacco to fall between the elements 3 on to the back wall 21 of the receptacle 1 and thereafter into the trough 22 from which they are fed into the auxiliary hopper 26. The long shreds of tobacco are fed upwardly in steps by the elevating elements 3 and are fed to the feeding roller 2 at a constant rate, thus ensuring that a definite quantity of tobacco is always fed to the feeding roller 2.

The short shreds are conveyed upwardly to the auxiliary hopper 26 and according to the quantity of shorts present in the tobacco so the amount of short shreds which are deposited over the mass of long shreds in the main hopper is regulated. The opening 28, however, in the auxiliary hopper may be adjusted by means of the adjustable base plate 31 so that if too great an accumulation of short shreds occur in the auxiliary hopper, the base plate 31 may be opened so as to allow the short shreds of tobacco to be fed on the mass of long shreds of tobacco in the main hopper. If, however, the short shreds of tobacco are only present in a small quantity, the slot 28 may be reduced in order that a line of short shreds may be fed over

the long shreds for the entire length of the hopper.

It will be appreciated that in the construction hereinbefore set forth, it would be possible to maintain one set of elements 3 stationary allowing the remaining set to reciprocate, and it is to be understood that such a construction is to be considered as a modification which comes within the ambit of the present invention.

It will be appreciated that the action of the elements 3 hereinbefore described is to raise the tobacco from the receptacle 1 into the hopper of the cigarette making machine and simultaneously loosen the tobacco whilst it is being elevated, and in addition separates the long and short shreds of tobacco from one another, thus the long shreds of tobacco which are fed to the hopper are opened out before they are fed into the main hopper.

It will be appreciated that as the elevating elements 3 are operating continuously, the long shreds of tobacco will be fed into the main hopper at a rate slightly in excess of the main tobacco consumed by the carding mechanism of the tobacco apparatus, therefore the excess of tobacco will periodically fall from the main hopper back into the receptacle 1, and as this tobacco is that which has been treated by the feeding roller of the combing roller 29 and the brushing roller, the same is liable to be formed into a dense mass and therefore the return of the same to the receptacle 1 enables the tobacco to be loosened by the separating elements in its passage to the main hopper.

What I claim as my invention and desire to secure by Letters Patent is:—

1. In a tobacco feeding apparatus for a cigarette making machine, a hopper, and means for feeding tobacco to said hopper and simultaneously effecting separation of the short and long shreds of tobacco.

2. In a tobacco feeding apparatus for a cigarette making machine, the combination with a hopper, of a conveyor for separating out the short shreds of tobacco and feeding long shreds only to said hopper.

3. A method of separating the long from the short shreds in tobacco, which comprises applying a series of intermittent impulses to different portions of a mass of tobacco to impart a forward movement to the whole mass for loosening the tobacco, and permitting the short shreds to fall.

4. In a tobacco feeding apparatus for a cigarette machine, the combination with a hopper, of a conveyor for advancing the tobacco step by step to the hopper and simultaneously separating out the short shreds of tobacco.

5. In a tobacco feeding apparatus for a cigarette making machine, the combination with a receptacle for tobacco, of a hopper located above said receptacle, and a conveyor

- for elevating the tobacco from the receptacle to the hopper and simultaneously separating out the short shreds of tobacco.
6. In a tobacco feeding apparatus for a cigarette making machine, the combination with a hopper, of means for feeding tobacco to said hopper and for separating out the short shreds of tobacco, an auxiliary hopper, and means for conveying the separated short shreds to said auxiliary hopper. 10
7. In a tobacco feeding apparatus for a cigarette making machine, the combination with a hopper, of a conveyor for separating out the short shreds of tobacco and feeding the long shreds only to said hopper, and means associated with said conveyor for distributing the separated short shreds over the long shreds in said hopper. 15
8. In a tobacco feeding apparatus for a cigarette making machine, the combination with a receptacle for tobacco, of a hopper above said receptacle, a conveyor for elevating the tobacco from the receptacle into the hopper, said conveyor serving to separate out the short shreds of tobacco, and means for elevating the short shreds and distributing them uniformly over the long shreds in the hopper. 20
9. In a tobacco feeding apparatus for a cigarette making machine, the combination with a receptacle for tobacco, of a hopper above said receptacle, a conveyor for elevating the tobacco from the receptacle into the hopper, said conveyor serving to separate out the short shreds of tobacco, an auxiliary hopper disposed above said first mentioned hopper, and means associated with said conveyor for elevating the short shreds into said auxiliary hopper for uniform distribution over the long shreds in said first mentioned hopper. 25
10. In apparatus for treating tobacco for use in a cigarette making machine, the combination with a plurality of spaced movable elements for receiving tobacco thereupon, of means for reciprocating adjacent elements in opposite directions for loosening the tobacco and causing the short shreds to fall between said elements. 30
- 45 11. In apparatus for treating tobacco for use in a cigarette making machine, the combination with a plurality of spaced elements for receiving tobacco thereupon, of a plurality of cranks supporting said elements, and means for rotating the cranks associated with adjacent elements at the same speed but with a phase difference of substantially 180 degrees for loosening the tobacco and causing the short shreds to fall between said elements. 50
- 55 12. In a tobacco feeding apparatus for a cigarette making machine, the combination with a hopper, of a conveyor for separating out the short shreds of tobacco and feeding long shreds only to said hopper, said con- 60
- veyor comprising a plurality of elements extending longitudinally of the path of movement of the tobacco and being spaced in a direction transverse to such movement, and means for reciprocating adjacent elements in the direction of their length for loosening the tobacco and causing the short shreds to fall between said elements. 70
- 75 13. In a tobacco feeding apparatus for a cigarette making machine, the combination with a hopper, of a conveyor for separating out the short shreds of tobacco and feeding long shreds only to said hopper, said conveyor comprising a plurality of elements extending longitudinally of the path of movement of the tobacco and being spaced in a direction transverse to such movement, a plurality of cranks supporting said elements, and means for rotating the cranks associated with adjacent elements at the same speed but with a phase difference of substantially 180 degrees for loosening the tobacco and causing the short shreds to fall between said elements. 80
- 85 14. In a tobacco feeding apparatus for a cigarette making machine, the combination with a hopper, of a conveyor for separating out the short shreds of tobacco and feeding long shreds only to said hopper, said conveyor comprising a plurality of elements extending longitudinally of the path of movement of the tobacco and being spaced in a direction transverse to such movement, a plurality of cranks supporting said elements, and means for rotating the cranks associated with adjacent elements at the same speed but with a phase difference of substantially 180 degrees for loosening the tobacco and causing the short shreds to fall between said elements, and means for elevating the short shreds and distributing them uniformly over the long shreds in the hopper. 90
